IRONING MACHINE

William J. Asher, Colorado Springs, Colo.

Application February 20, 1929. Serial No. 341,510

21 Claims. (Cl. 68—9)

This invention relates to ironing machines and more particularly to the type adapted to handle articles which vary in size, shape and thickness.

In ironing machines of this character, wrinkling has been one of the greatest problems, and the problem has been complicated by the desirability of having the machine capable of handling not only flat articles such as sheets, blankets and handkerchiefs, but also garments of irregular 10 shape or provided with buttons. Obviously, the provisions for preventing the breaking of buttons and for handling a varied character of work render it very difficult to prevent wrinkling for all types of work.

15 It has been proposed to provide a power ironing machine with a single roller for effecting a simultaneous adjustment of the tension of both aprons which guide the work in its path through the machine. In practice, the aprons stretch or 20 contract unequally and hence the single adjustment was not entirely satisfactory. In the present machine, means are provided for adjusting each of the aprons independently of the other, so as to keep each apron under the exact necessary 25 tension.

It is therefore the object of the present invention to provide a power ironing machine with means for adjusting the aprons independently, whereby wrinkling of the work is avoided.

30 It has been customary to provide two ironing cylinders each provided with aprons which carry the work around one cylinder and then convey it to the second cylinder and present it thereto. Various paths for these aprons have been proposed, and heretofore it was thought desirable for 35 various reasons to have the aprons make a sharp angle in the path between the cylinders. However, it is believed that this arrangement of the aprons causes the greater portion of the wrinkling of the goods which was met with in practice.

The present invention contemplates the bringing of the two aprons together to secure the goods, at a point immediately above the first cylinder and passing the aprons together toward the bottom of the second cylinder along a plane which is as nearly as possible horizontal.

It is therefore the object of the present invention to provide means for transmitting the work from one cylinder to another without wrinkling 50 the work.

The relative speeds of the various parts is of considerable importance, and the applicant has developed the ratios which produce the most satisfactory results. In this respect it has been 55 found desirable to increase slightly the speed as

the articles pass from one moving element to another, and hence each succeeding element is driven at a speed slightly greater than the element from which the article is passing.

It is therefore another object of the invention 60 to provide a slightly increased speed for the greater number of the moving elements of the machine, in the order in which they come into contact with the goods in their passage through the machine.

At the front end of the machine an apron loosening roll is provided for one of the cylinder aprons, which roll, together with the doffing knives and its associated rolls, are all mounted upon a rocking frame. Doffing tapes are mounted 70 upon a roller carried by this frame so as to coat with the cylinder apron to hold the articles thereon in transit from the first cylinder to the point where the two cylinder aprons meet to receive the goods. A tensioning roller is provided 75 for the doffing tapes so that when the rocking frame is raised to permit access to the doffing bar or to relieve the tension in the cylinder apron, the gravity actuated tensioning device will function to tension the doffing tapes at the same time. 80 Hence, whenever the operator raises the rocking frame, both the apron and the tapes are automatically tensioned, and it is not possible for an operator to neglect tensioning these elements when getting ready to operate the machine.

It is therefore a further object of the invention to provide a tensioning device for the doffing tapes associated with the apron at the front end of the ironing machine, whereby the tapes are automatically tensioned when the doffing knives 90 are raised.

With the former machines the ironed goods discharged at the delivery end were so highly heated from the ironing, that the hands of the operators would be burned when these articles 95 were grasped without first being allowed to cool. This difficulty is avoided in the present invention by a cooling device which receives the highly heated articles from the apron and passes them upon a series of tapes to a receiving board or 100 table. Provision is made for the access of the air to almost the entire surface of the articles in transit through this mechanism, which has an agitating portion to wave the articles to and fro. This arrangement cools the articles much more 105 rapidly than when passing in a simple transitory path, and articles discharged thereby are sufficiently cooled to be easily handled.

It is therefore another object of the invention to discharge the articles from the ironing ma- 110

chine in a cooled condition so as to permit comfortable handling thereof.

Other objects and features of novelty will be apparent as the following description proceeds, 5 when taken in connection with the accompanying drawings, in which:

Figure 1 is a side elevation of the entire power operated ironing machine according to the present invention;

10 Figure 2 is a diagrammatic view of the rolls and aprons employed in the present machine, showing the path of the aprons through the machines;

Figure 3 is an enlarged detail view of the front 15 or feeding end of the machine, showing the doffing bar and the tensioning devices for the aprons;

Figure 4 is an enlarged detail view of the delivery portion of the machine, showing particularly the cooling device; and

20 Figure 5 is a partial section on line 5—5 of Fig. 4.

The general arrangement and proportions of the machine will be evident from an inspection of Fig. 1 of the drawings. All the operating parts 25 are mounted in parallel side walls of a large frame, the near wall of which is indicated at 10. The frame is provided with a bottom portion 11 which may be mounted upon a substantial base, although there is little vibration due to the operation 30 of the machine, inasmuch as all of the larger operating parts merely rotate about fixed axes. The side members such as 10 have numerous openings for the reception of shafts, etc., and other openings are provided for lightening. Two 35 of these openings are indicated at 12 and 13 respectively, and it will be understood that corresponding openings are provided in the opposite side of the frame, as the two side members are substantially symmetrical. Supported upon the 40 lower edges of the four openings are four bearings, each of which is indicated generally at B. The opposed bearings of each pair are in axial alignment and serve to support for rotation the cylinders 14 and 15. These cylinders 14 and 15 45 are heated by steam or other heating agents in any well-known manner, such as by steam introduced through the supply pipe shown at 16 so as to constitute the ironing cylinders. The cylindrical faces of these members constitute ironing 50 surfaces for the goods which pass through the machine. They are driven in opposite directions forming constantly operating walls and at slightly different speeds. In actual operation of the machine the cylinder 14 is driven faster than the 55 cylinder 15 by the arrangement of the drive gearing now to be described.

The drive pulley for both cylinders is indicated at 17, and may be driven by any suitable source of power, and provided with a clutch 60 mechanism of a known type by which the pulley may be operatively engaged with or disengaged from the drive shaft 18 of the machine. Upon this shaft 18 is rigidly secured a pinion 20 which meshes with a gear wheel 21 fixed upon an idler 65 shaft 22. The teeth of the gear 21 mesh with those of a second gear 23 mounted upon an idler shaft 24. Idler shafts 22 and 24 carry pinions 25 and 26 respectively, which pinions are in engagement with large gears 27 and 28 which are 70 fixed upon the axles of the heated cylinders. From this arrangement of gearing it follows that the cylinders are driven in opposite directions at substantially the same speed. However it will also be observed that the gear wheel 21 75 is of slightly less diameter than the gear wheel

23. Since the pinions 25 and 26 are the same size, this results in the cylinder 14 being driven at a somewhat faster rate of speed than the cylinder 15.

Associated with each of the cylinders is an endless apron. The apron of the first cylinder is indicated at 50, and that of the second cylinder at 51. These aprons are guided over rollers hereinafter to be fully described and are employed for the purpose of holding the articles to be ironed in close contact with the cylinders as the cylinders revolve about their axes. The aprons further cooperate in transferring the goods, ironed on one side by the first cylinder, to the second cylinder where the articles are ironed on the opposite side. The aprons may be of various materials, as is well-known, but with the arrangement of pressure and guide rollers which I employ in the present machine, the relatively inexpensive cotton aprons may be employed with 85 very satisfactory results. The arrangement of aprons is most clearly illustrated in Fig. 2. Here the end of the feed board is indicated at 52 overlying the feed basket 44, and this end is shown to be positioned in close proximity to the feed tape roll 45, over which pass the feed tapes 46. These tapes conduct the fed articles to the first pressure roller 53 associated with the cylinder 15, and constituting the apron feed roll. A safety roll 47 is mounted above the tapes 46. 90

The apron 50 passes around pressure roller 53 moving in the direction indicated by the arrow and articles passing from the feed tapes 46 on to the top of pressure roller 53 are drawn downwardly between the apron 50 and the outer 100 cylindrical ironing surface of cylinder 15. This cylinder is in constant rotation and the endless apron 50 constantly passes on to the same at one point, i. e., between pressure roller 53 and the cylinder, and is constantly removed at another 105 point, i. e., adjacent the apron drive roll 54. 110

Very nearly the entire surface of the cylinder, therefore, is covered by the apron and the goods being ironed are tightly pressed thereby, during the period of their travel around the cylinder 115 axis, against the cylinder. In addition to pressure roller 53, additional pressure rollers are provided indicated respectively at 48, 55, 56 and 57, the function of these rollers being solely to press the apron tightly against the cylinder. The 120 rollers are therefore provided with layers of relatively soft materials on their surfaces, such as rubber or cloth. 125

After the articles being ironed have passed around the cylinder 15 from pressure roller 53 130 to the proximity of the drive roller 54, they are removed from the ironing surface by the doffing knives 58 mounted upon a series of pads 59 that are pivoted to the transversely extending doffing bar. They are next conveyed over and to the 135 rear of the cylinder 15 by the apron 50 and its cooperating tapes 60, clearly shown in Figs. 2 and 3. These tapes are spaced between the doffing knives 58, and their spaced relation permits escape of free steam from the articles being 140 ironed at this portion of their path of travel.

The articles are delivered by the apron 50 and the tapes 60 to a point adjacent the guide roller 61 positioned immediately above the first cylinder 15, and at this point are for the first 145 time also engaged by the second apron 51 which likewise passes over roller 61. Thus held between the two aprons the articles being handled pass downwardly, under the guide roller 62, and the pressure rollers 63 and 64 of the second cyl- 150

inder to the point over the roller 64 where the aprons separate. The first apron 50 passes over the guide roller 65, take up roller 66, guide rollers 67, 68 and 69 and outside of the pressure rollers 57, 58, 55 and 53, and returns to the first cylinder in the direction of the arrow.

The second apron 51 passes around roller 64 on to the surface of the cylinder 14, and is held thereagainst by the pressure rolls 64, 63 and 49, 10 and then leaves the cylinder over the apron drive roller 70, guide roll 71 and drive roll 72, adjusting roll 73, and guide roll 74, thence downwardly over the common guide rolls 61 and 62. The articles, after being ironed by both cylinders are 15 removed from the surface of the second cylinder by doffing knives indicated at 75 and delivered by means to be hereinafter described.

It should be noted that the two aprons 50 and 51 travel together between the cylinders 14 and 20 15 along a predetermined and unchanging path, as each of the rolls 61, 62, 63 and 74 are mounted on fixed axes. There are no adjustable rolls in the common path, as the take up rolls 66 and 73 are located in the return paths of their respective aprons. By having the two aprons come together above the first cylinder, and not separate or turn until under the second cylinder, a very long flat reach is provided. The contact of the two hot aprons with the goods for this long 30 reach facilitates the drying of the goods.

Where the two aprons separate, after conveying the goods to the second cylinder, a doffing brush 43 is mounted in contact with the first apron where it passes over the roller 65 so as to remove 35 any articles which tend to cling to the first apron and cause them to drop onto the second apron to be carried thereby to the second cylinder.

The apron 50 is driven from the first apron 40 drive roller 54, which is driven from the first cylinder drive gear 23, through the intermediate gears 39 and 40 shown in Fig. 3. The gear 40 meshes with the gear 41 which rotates with the roller 54. As the roller 54 is of greater diameter 45 than the gear 41, the speed of the apron 50 is slightly greater than the peripheral speed of the cylinder 15. The cylinder is also larger than the gear 28 but the different ratio gives the greater speed.

50 The apron 51 is driven from the second apron drive roll 72, which carries a sprocket 30 of slightly smaller diameter driven by a chain 31 passing over idler sprocket 32 in its path from a sprocket 33 carried by a gear 34 of slightly 55 smaller diameter which meshes with the second cylinder drive gear 27. This arrangement drives the apron 51 at a speed slightly greater than the peripheral speed of the cylinder 14.

The mounting of the auxiliary tapes 60 is 60 clearly shown in Fig. 3. Referring to this figure, a rocking frame 80 is shown as mounted on a pivot 81 above the front portion of the cylinder 15. This frame has journaled therein the axis 82 of the drive roll 54 for the apron 50 and the axle 83 of the doffing tape drive roll 84. Doffing knife pads 59 are supported by a bar that is fastened to a pair of brackets bolted direct to either main frame 10. The frame 80 is further provided with extensions 90 to which are pivoted 65 shorter arms 91 providing journals for the axle of the doffing tape pinch roll 92.

70 It will be apparent that the apron 50 coming off of the cylinder 15 passes around the drive roll 54 and extends back over the cylinder, and 75 passes over the bare apron roll 61. The doffer

tape 60 which passes between the doffing knives 58 extends around the roll 54 on top of the apron 50, but leaves it before it reaches the roll 61 and passes back over the drive roll 84, being forced thereagainst by the pinch roll 92. The 80 doffing tapes 60 are slack beyond the drive roll 84, and pass under the doffing bar and pads 59 and extend up around them and pass between the doffing knives 58 and extend therebeyond to overlie the apron drive roll 54.

The bight of the doffing tape 60 passes over the doffing tape stretch tube 93, the journals of which are carried by freely pivoted arms 94, the pivotal supports of which are adjustably secured by bolts 95 in slots 96 in each of the main side frames of the machine. This arrangement provides for the tensioning of the doffing tapes at the same time that the apron 50 is tensioned. It will be obvious from an inspection of Fig. 3 that the movement of the journal 82 up around the shaft 81 as a pivot will tend to stretch the apron 50, but the tension roll 66 (Fig. 2) will yield so as not to stretch the apron. The roll 93 for the doffing tapes is therefore mounted to be constantly acted upon by gravity, so as to permit the 90 doffing tapes to move with the apron 50 when it is tensioned. Hence the variation in the tension of the tapes 60, produced by the upward movement of the rolls 54 and 84 about pivot 81, will be taken up by the roller 93 under the influence 100 of gravity.

For the removal of the ironed goods from the machine, aerating tapes 100 are provided which are somewhat similar to the doffing tapes 60, and their arrangement is shown in detail in Fig. 4. 110 These tapes pass between doffing knives 75 carried by the doffing pads 101 and pass over the aerating tape drive roll 102 which is journaled upon a shaft 104 in an arm 103 rigid with the main frame of the machine. A pair of swinging 115 arms 105 are pivoted on each end of the shaft 104 and terminate at their lower ends in sleeves 106 which slidably receive rods 107, carrying rollers 108 journaled between their ends. Each of the sleeves 106 carries a lug 106' to one of which 120 is pivoted a connecting rod 109, which at its other end is eccentrically pivoted on a disc 110. Also pivoted to the lugs 106' are sleeves 112 carrying sliding arms 113 having rollers 114 journaled in their lower ends.

The aerating tapes 100, passing between the doffing knives 75, extend over the drive roller 102 and down under the roller 114, then pass upward over a bare roll 115 journaled in the arm 103, and then back under the doffing bar 130 and pads 101.

Cooperating with the aerating tapes 100 are aerating tapes 120 which also pass over the roller 102 outside of the tapes 100. The outer tapes 120 then pass down around the roller 108, and 135 up over an adjustable take up roller 121, which is journaled in the outer ends of sliding rods 122 carried by sleeves 123 rigidly secured to the arm 103. The forward ends of the auxiliary tapes then pass around a driving roll 125 journaled in 140 arms 126 integral with the arms 103.

The disk 110 is provided with sprocket teeth, and serves to drive both sets of aerating tapes, as well as to oscillate the swinging arm 105. A drive chain 140 driven by the sprocket 110 passes 145 over an idler 141 carried by the arm 131, which swings about the center of roll 125 and then passes under the sprocket 142 which drives the roll 125 and the outer tapes 120. The chain 140 then passes over sprocket 143, which drives the 150

inner tape driving roll 102, and its tapes 100. The arm 131 carries the brush roll and adjusting arm for the idler sprocket to take up slack in brush roll drive chain.

5 Rigid with the disk 110 is a gear 144 meshing with a pinion 145 keyed on a shaft 146 journaled in one of the side frames 10. Also keyed on this shaft is a smaller gear 147, which meshes with the second cylinder drive gear 27. With this arrangement the doffer tapes 100 and the aerating tapes 120 are driven at speeds slightly greater than the surface speed of the cylinder 14.

10 It will be readily apparent that the articles held against the cylinder 14 by the apron 51 will be removed therefrom by the doffing knives 75, slightly below the point where the apron 51 leaves the cylinder 14 and passes back around the roll 70. The ironed articles will then be carried away by the aerating doffing tapes 100. However, some 15 articles may tend to cling to the apron 51 as it passes upwardly around the roll 70, and to positively remove these articles a doffing brush 43 is mounted to engage the tapes at this point. The doffing brush shaft is journaled in arms 131 adjustably carried by the threaded arms 132 and 25 133 pivotally secured to the main frame of the machine.

20 A sprocket 135 is keyed on the doffing brush shaft and receives a chain 136 which passes over a take up idler sprocket 137, and a drive sprocket 138 secured to the bare apron roller 70, which in turn is driven by suitable gearing from the main gear 27. Thus the doffing brush 130 is driven at a much greater speed than the apron 51, and in the 25 opposite direction so as to effectively dislodge from the apron any articles tending to cling thereto, and drop them onto the doffing tapes 100.

25 The ironed articles on the tape 100 pass beneath the roller 125 and engage the auxiliary tapes 120. Then the two sets of tapes 100 and 120 together convey the ironed articles up over the roll 102 and down to the rollers 114 and 108. As the ironed articles pass down beyond the roller 102, they are subjected to a waving, to and fro motion, due to the oscillation of the arm 105, which is imparted to the rollers 114 and 108 and the tapes carried thereby. The oscillation of the arm 105 is transmitted by the bar 109 from the disk 110 on which it is eccentrically mounted. 30 The relatively long path from the doffing knives 75 to the roller 102, the spaced relation of both sets of aerating tapes 100 and 120, and the final agitation in their downward path to the rollers 114 and 108 cools the ironed goods; so that when 35 they are delivered to the folding board 139, they are in condition to be handled with no discomfort.

40 The folding board 139 is located directly under the delivery device which, as shown in Fig. 2, is close to the reach of the apron 50 between rollers 65 and 66. To prevent misplaced articles from fouling the apron at this point, a guard 149 is mounted at the rear end of the folding board to confine the articles thereon so as to constitute a 45 receiver for the ironed goods.

45 The means for driving the doffing brush 43 is shown in detail in Figure 5. It will be observed that a pinion 150 mounted on the doffing brush shaft 151 meshes with a gear 152 fixed on counter shaft 146 so that the doffing brush is driven by power taken from the large ring gear 27.

50 Having thus described the invention, what is claimed as new and desired to be secured by Letters Patent is:

55 1. In an ironing machine, in combination, two

spaced ironing cylinders, an apron associated with each of said cylinders, a plurality of rollers for guiding said aprons in unchanging substantially straight parallel downward paths to carry the goods being ironed from adjacent the periphery of one cylinder to adjacent the periphery of the other, and independent gravity actuated automatic tensioning rollers located in the return paths of the respective aprons.

60 2. In an ironing machine, in combination, a frame, an ironing cylinder, an apron associated therewith, a roller over which said apron passes, doffer tapes contacting with said apron, a pivotal mounting for said roller permitting it to be raised, a roller over which the doffing tapes pass, arms rotatably supporting the ends of said roller, and means carried by the frame upon which the arms are pivotally mounted, said means being adjustable in the frame.

65 3. In an ironing machine having an ironing cylinder, an apron, and a roll over which said apron passes from said cylinder, said roll having a pivotal mounting permitting it to be raised from the cylinder, the combination of doffing tapes overlying said apron on said roll and extending along the apron, a member for supporting and guiding said tapes, a pair of arms carrying journals for said member, bolts forming pivotal mountings for said arms, and slots in the machine frame adjustably receiving said bolts.

70 4. In an ironing machine, in combination, a cylinder, an apron associated therewith for holding the goods thereagainst to be ironed, a rocking frame pivoted above said cylinder carrying a roller over which said apron passes, whereby 100 rocking of the frame tensions the apron, a stripping means and doffer tapes associated with said stripping means for holding the goods on said apron after they are stripped from the cylinder, and a gravity actuated tensioning means for said 110 doffer tapes.

75 5. In an ironing machine, in combination two spaced ironing cylinders, an apron associated with each of said cylinders, each apron adapted to carry the goods being ironed around its cylinder, 120 and both aprons cooperating to carry the goods from the first cylinder to the second, means for stripping the goods from the first cylinder, doffer tapes associated with said stripping means adapted to hold the goods on the first apron until it is 125 engaged by the second, and a pivotally mounted roller over which said doffer tapes pass, which serves as a gravity tensioning device for said doffer tapes.

80 6. In combination with an ironing machine 130 having an ironing cylinder and an apron passing substantially around its periphery and leaving the cylinder to pass around an apron roll, a doffing knife below said apron roll, doffing tapes passing below said knife, a rocking frame pivoted to said ironing machine frame and carrying said apron roll, and a roll for said doffing tapes, whereby upward movement of said frame moves said rolls away from said cylinder and releases the tension in said apron, a swingable roll over which said doffing tapes pass, said swingable roll serving to tension said tapes as the apron is tensioned.

85 7. In combination with an ironing machine, 145 means for delivering ironed articles therefrom, comprising a pair of conveyors each comprising a set of parallel tapes permitting access of air to said articles in transit, and having a common path for their contiguous sides and means for 150

simultaneously oscillating said conveyors together at a portion of the common path.

8. In combination with an ironing machine, means for delivering ironed articles therefrom, comprising an elevated roller spaced from the ironing mechanism of said machine and a swinging arm pivoted at the axis of said roller, a pair of rollers carried by said swinging arm, endless tapes passing together over said elevated roller and respectively over said pair of rollers, and means for oscillating said swinging arm from a driven element of the machine.

9. In combination with an ironing machine, means for delivering ironed articles therefrom, comprising an elevated roller spaced from the ironing mechanism of said machine and a swinging arm pivoted at the axis of said roller, a pair of rollers carried by said swinging arm, endless tapes passing together over said elevated roller and respectively over said pair of rollers, and means for oscillating said swinging arm from a driven element of the machine, said pair of rollers being respectively carried by said swinging arm by slidble connections, whereby their weight serves for gravity tensioning of their respective tapes.

10. In combination with an ironing machine including a rotating drum and apron associated therewith and having a cooling device adapted to receive goods ironed by the machine and deliver them in a cooled condition for handling, a rotary brush for doffing the goods from the ironing machine apron and causing them to fall into position to be engaged by said cooling device.

11. In combination with an ironing machine comprising a cylinder and an apron extending substantially entirely therearound, said apron leaving the cylinder at a point above the point where it passes on to the cylinder, a knife for separating the goods from the cylinder, and a doffing brush for separating the goods from the apron.

12. In combination with an ironing machine having an ironing cylinder and an apron for holding the articles being ironed thereagainst for a part of its periphery, said apron leaving said cylinder and passing around an apron roll, a doffing knife below said apron roll for removing the articles from said cylinder, tapes passing under said doffing knife to deliver the articles from the machine, and a doffing brush in contact with said apron roll to prevent the articles from being carried away by said apron and insuring their delivery by said tapes.

13. An ironing machine comprising in combination, a pair of cylinders each having an apron passing substantially around the periphery thereof, then leaving its cylinder and passing to a point adjacent the periphery of the other, said aprons having a common path to convey articles being ironed from the first cylinder to the second, and a doffing brush located above the end of the common path to prevent the articles adhering to the first cylinder apron and insuring their passing to the second cylinder upon its apron.

14. In an ironing machine comprising in combination a pair of spaced ironing cylinders, an apron passing substantially around the periphery of each of said cylinders to hold the goods being ironed thereagainst, means for bringing said aprons together between the cylinders to transfer the goods from one cylinder to the other, the combination of means for driving the second cylinder slightly faster than the first cylinder, and means

for driving each of said aprons slightly faster than its associated cylinder.

15. In an ironing machine, in combination, two ironing cylinders, a first cylinder and a second cylinder, horizontally spaced apart and mounted to rotate in opposite directions about parallel axes, two endless aprons, one associated with each cylinder, and means for guiding the aprons so that they move along closed and substantially fixed paths in the operation of the machine, a portion of each apron extending substantially around the cylinder with which it is associated, at all times, to hold flat goods against the cylindrical surface thereof, the first apron, after leaving the first cylinder, passing over the top of this cylinder and beneath the second cylinder, and the second apron, after leaving the second cylinder, passing over the top of this cylinder and to a point above the first cylinder where it meets the first apron, both aprons then passing in close parallel relationship downwardly from this meeting point and under the second cylinder to a parting point adjacent the second cylinder, whereby the goods which have passed around the first cylinder are conducted and delivered to the second.

16. In an ironing machine, in combination, two ironing cylinders, a first cylinder and a second cylinder, horizontally spaced apart and mounted to rotate in opposite directions about parallel axes, two endless aprons, one associated with each cylinder, and means for guiding the aprons so that they move along closed and substantially fixed paths in the operation of the machine, a portion of each apron extending substantially around the cylinder with which it is associated, at all times, to hold flat goods against the cylindrical surface thereof, the first apron, after leaving the first cylinder, passing over the top of this cylinder and beneath the second cylinder, and the second apron, after leaving the second cylinder, passing over the top of this cylinder and to a point above the first cylinder where it meets the first apron, both aprons then passing in close parallel relationship downwardly in substantially straight paths from this meeting point to a point beneath the second cylinder, the parallel aprons making, between these two points, such angles with the horizontal that goods held therebetween are supported thereby against downward sliding movement relatively to the aprons under the influence of gravity, the aprons then continuing to a parting point adjacent the second cylinder.

17. In combination with an ironing machine and the ironing apron thereof, means for delivering ironed articles therefrom comprising a conveyor including two sets of endless tapes, means causing portions of said tapes to move in parallel adjacent paths so as to engage and frictionally retain articles therebetween in such manner that large areas of both sides of each article are exposed to the atmosphere to permit cooling of the articles in transit by contact with the atmosphere.

18. In combination with an ironing machine, means for delivering ironed articles therefrom comprising two sets of endless tapes, guide means for said tapes whereby they are caused to move in parallel adjacent paths for portions of their lengths and to receive and retain between them ironed articles, and means for oscillating portions of the tapes which retain such articles between them and thereby bodily oscillating such articles to effect cooling thereof.

19. In combination with an ironing machine, means for positively moving the goods from the ironing element, means for receiving said ironed

goods and conducting them to a folding board comprising two sets of tapes, means for guiding portions of said sets of tapes respectively in closely adjacent parallel paths so as to frictionally grip and retain between them articles which have been ironed so as to permit access of the air to substantially the entire surface of the goods conducted thereby, whereby the goods are cooled sufficiently for comfortable handling at the folding board, and means for supporting and oscillating article retaining portions of said tapes to give the goods a to-and-fro waving motion to facilitate cooling.

20. The combination with an ironing machine having a pair of ironing cylinders and a pair of aprons for conducting the articles being ironed from one cylinder to another, the first apron passing off of the first cylinder and the second apron passing on to the second cylinder, said 20 aprons having a common path adjacent the second cylinder and separating adjacent the second cylinder, the second apron passing on to the second cylinder, of a doffing brush positioned to act upon the first apron, after it has separated from

the second and at a point directly above the second apron, for dislodging articles from the first apron and causing them to be deposited by gravity upon the second apron.

21. In combination with an ironing machine, mechanism for conducting the ironed goods to a receiver, said mechanism including tape supporting means, two sets of movable endless tapes mounted on said means, each tape of one set having a reach disposed parallel to and closely adjacent a reach of a tape of the second set and extending longitudinally in the same direction so that goods interposed therebetween may be engaged and transported by the tapes, the tapes of each set being spaced apart at such intervals that the greater part of the surfaces thus conveyed is exposed to the air, the tape supporting means comprising an oscillating element for supporting portions of the tapes which are for the time being in contact with the goods so that the goods may be given an oscillatory or waving motion when transported.
